ALBERT WEIGAND LUHRS, OF NORTH BERGEN, NEW JERSEY, ASSIGNOR TO METAL
DIAGONALS CORPORATION, OF NEW YORK, N. Y., A CORPORATION OF NEW YORK.

SHIPPING CRATE.

Application filed June 9, 1923. Serial No. 644,318.

To all whom it may concern:

Be it known that I, ALBERT WEIGAND LUHRS, a citizen of the United States, residing in North Bergen, county of Hudson, 5 and State of New Jersey, have invented certain new and useful Improvements in Shipping Crates, of which the following is a specification.

This invention relates to a shipping crate 10 and more particularly to a crate having an improved form of bracing for increasing the strength of the crate.

Shipping crates are generally made up of framework of lumber and are usually provided with sheathing in the form of slats or fillers to cover partially or completely the faces of the crate for the purpose of protecting the contents.

Heretofore the crates have sometimes been 20 braced by means of a wooden strip or strips applied diagonally across one or more faces of the crate. But this method of bracing has never been in general practice for many reasons. In the first place, these wooden 25 diagonals materially increased the weight of the crate, which increase resulted in greater cost of freightage or other transportation. They were expensive both in cost of material and in the cost of labor necessary for fitting them to the crate and sawing them off so that their ends were flush with the crate surface.

In practical use, moreover, the crates so braced were unsatisfactory because the ends 35 of the diagonals were liable to be pried loose while the crates were being handled, and they usually could not be stacked very satisfactorily because the braces, owing to their thickness, projected over the faces of the 40 crate and thus permitted the same to rock during transit.

The present invention contemplates the provision of an improved mode of bracing for the crate, with the object of not only 45 eliminating the difficulties brought about by the wooden braces above described, but also providing a far stronger, lighter and cheaper form of construction.

A good understanding of the invention 50 may now be had from the following descrip-

tion, having reference to the accompanying drawings, in which—

Figure 1 is a perspective view of the top face of a crate braced in accordance with one form of the present invention; 55

Figures 2 and 3 are perspective views of the side faces of crates braced in accordance with modifications of the present invention;

Figure 4 is a perspective view of a corner of a crate braced in still a different manner; 60

Figures 5 and 6 are plan views of the faces of crates showing two ways in which the bracing and slats of the sheathing may be interlaced; and

Figure 7 illustrates an application of the 65 bracing to elongated crates.

Similar characters of reference designate similar parts in each of the several views.

In each of the views the framework of the crate is shown as being made up of a 70 number of frame members consisting of strips of wood or other suitable material, these members being fastened together in any suitable manner approved in modern practice of crate construction. 75

In the form of construction illustrated in Figure 1, the two frame members 10 and 11 are fastened to the edges of two similar members 12 and 13, members 10 and 11 being spaced a short distance from the ends 80 14, 15, 16 and 17 of the members 12 and 13. This spacing provides room for fastening the frame members 18 and 19, 20 and 21 to the members 10, 11, 12 and 13. The corner of a crate constructed in this manner is indicated in the lower part of Figure 1, from which it will be seen that each of the three wooden strips forming the edges defining the corner is nailed to the other two strips. Good practice in making these crates requires that at least two nails be driven 90 through the flat sides of one strip into the edges of the adjoining strip. These nails are indicated in the drawing by the dots 22.

Although Figure 1 illustrates only one 95 face of the crate, it will be understood that the other faces are made in a corresponding manner, as shown for example, by Figures 2 and 3 which illustrate the side faces of a corresponding framework.

It will be understood, however, that the invention is not limited to the use of a crate having the particular form of framework or corner construction illustrated in the drawing, but may be employed with other forms of construction known in the art of crate manufacture.

With reference to Figure 1, it will be observed that the framework therein illustrated is capable of resisting strains in a direction *a*, *b* or *c*, *d*, by virtue of the frame members 12 and 13, and in a direction *a*, *d* or *b*, *c*, by virtue of frame members 10 and 11. The framework, however, is not reinforced against diagonal strains, as for example in the direction *a*, *c* or *b*, *d*, and it is this weakness in the framework construction which is cured by the present invention.

In the form of embodiment of the invention illustrated in Figure 1, a piece 24 of sheet metal strapping is fastened to the frame members 12 and 13 by means of a single nail 25 and 25^a, respectively, driven through the strapping into the narrow faces or edges of the said frame members 12 and 13, respectively. A similar diagonal strap 27 is fastened to the opposite ends of the frame members 12 and 13 by nails 28 and 28^a. These metal straps serve effectively for reenforcing the framework against all stresses in a diagonal direction, strap 24 serving to provide against compressive stresses in the direction *a*, *c* and strap 27 serving to resist compressive stresses in the direction *b*, *d*.

The metal straps may be made from any suitable material and may be either annealed or unannealed steel, or they may be iron or other suitable metal. The width and thickness will depend, of course, upon the particular use for which they are intended. For example, for crates such as suitable for shipping furniture, strapping three quarters of an inch wide and fifteen thousandths of an inch thick is most advantageous. For crates intended for shipping heavy commodities, thicker and wider straps may well be employed.

The form of strapping illustrated in Figure 1 has the advantage that it requires only a single long nail at each end of the strap, this nail being driven through the narrow side of the frame member. The strapping, therefore, has the added advantage over the wooden diagonal, hereinabove referred to, in that the frame member is less liable to be split by the single nail than it is by the two nails which would be employed for securing a wooden diagonal in the same place. Incidentally, a weakening of the diagonal itself caused by the use of two nails is overcome by the present construction.

Figure 2 shows the left-hand side of a crate similar to the crate of Figure 1, but

with a slightly different arrangement of reinforcing straps. The same reference characters have been applied to the corresponding parts of the frame in this figure. Here, the straps 29 are fastened to the outer flat faces of the members 18, 19, etc., of the crate. A plurality of short nails 30 may be used instead of the single nail which is employed for the braces 24, 27 of Figure 1. This form of construction has the advantage over that of Figure 1, in that it still further increases the strength of the crate and that because of the use of more and shorter nails, it reduces the liability of splitting the lumber. On the other hand, it is somewhat more costly to apply, because it necessitates the driving of several nails instead of a single nail.

Figure 3 shows the right-hand side of a crate similar to Figure 1, and with a still different arrangement of reenforcing straps. The straps 31 are longer than the straps 24, 27 of Figure 1, and in addition to being nailed to the narrow edges of the frame members, they are extended and secured to the exposed or flat faces thereof, as indicated at 32. Each end of each strap, therefore, is fastened by use of a long nail 33 and of a plurality of short nails 33'. This additional fastening of the straps increases still further the strength of the finished crate even though at slightly greater cost.

Figure 4 shows a corner of a crate braced in still another manner. The diagonal straps 34 in the present case are first nailed to the exposed flat faces of the frame members and are then passed across the ends of the members and over onto the side of an adjacent frame member. In this way, it is possible to fasten the straps in place by a still greater number of nails. This form of reinforcement is stronger than any of the other forms previously illustrated but is slightly more expensive to apply.

In the construction of Figure 4, the straps 34 may be continued from the one face of the crate and extended across an adjacent face, so that the operation of cutting a separate length of strap for each face is avoided. But in usual practice, I prefer to employ a separate length of strap for each face.

The sides of the crate may be left open, as shown in Figures 1, 2 and 3, or may be partially or entirely sheathed with a piece 120 of veneer, ply-wood, corrugated strawboard, fibre board or other suitable material, either with or without the use of wooden slats. The crate may also be sheathed with lumber which partly or completely fills the open 125 spaces in the framework.

Figures 5 and 6 illustrate two ways in which the metal straps may be interlaced with the slats used in the sheathing. In Figure 5 metal straps 24 and 27 are run 130

underneath certain of the sheathing slats, namely 35 and 36, and over other of the sheathing slats, namely 37. In Figure 6, the metal straps are carried outside of the sheathing slats 38 and 39, adjacent the frame members 18 and 19, and underneath the central sheathing slats 40. By thus interlacing the sheathing slats and the metal straps, it is possible to use lighter weight lumber in the sheathing and still afford greater protection to the contents of the crate than could be obtained without the use of the straps, even if much heavier lumber were employed. It is, of course, obvious that the showing of Figures 5 and 6 is merely illustrative of two of the many ways in which sheathing slats and reenforcing slats may be used on the crate. In certain instances, however, it may be advantageous to run underneath all of the sheathing so as to reenforce all of the sheathing against externally applied thrusts.

It is manifest that all sides of any particular crate need not be reenforced in the same manner, as it may be more convenient to use one type of reenforcement in one place and another type, or omit the reenforcement, in another part of the crate. In elongated crates such as illustrated in Figure 7, it may be found desirable to use a plurality of diagonals such as illustrated at 41.

The metal straps may be fastened to the framework either by nails, staples, screws or other fastening members, as is most convenient. One end of a strap may be fastened, as indicated in one of the figures of the drawings, while the other end may be fastened, as indicated in any of the other figures.

In practical operation, the straps may be cut from a roll, as needed, or they may be provided already cut in the proper length, and if desired, punched in various ways so that they may be easily applied. They have the advantage, therefore, over the wooden diagonals, that they require very little storage space, and the cost of handling is reduced to a very low figure.

The application of the straps to the crate is a very simple operation in comparison to the application of wooden diagonals which have to be carefully sawed off to fit whereas the straps may be merely cut off with shears. In comparison to the wooden diagonals, moreover, the straps have the advantage that they brace the sheathing against external forces, which bracing is impractical in most cases if wooden diagonals are employed. They have the further advantage that the thickness is practically nil, so that they do not protrude beyond the faces of the crate, as do the wooden diagonals, therefore permitting the surface of the crate to be flat, and they do not

bring about an increase in the crate dimensions.

The present invention, therefore, has the advantage of securing more effective bracing of the crate than is possible by wooden diagonals, at less cost of material, labor of application and transportation.

Although I have herein shown and described certain specific forms of embodiment of the invention, it will be expressly understood that many changes and modifications may be made within the scope of the appended claims without departing from the spirit and scope of the invention, it being my intention to claim the same as broadly as the state of the prior art will permit.

What I claim is:

1. In combination, a framework defining the edges of a crate and a plurality of metal straps for at least one of the faces for reenforcing said face against diagonal stress, said straps being disposed diagonally on the said face and having their ends secured to the framework adjacent the diagonally opposite corners of the face.

2. The combination according to claim 1, in which the framework constituting the said face of the crate comprises a plurality of strips of material forming the opposite edges of the said face, and in which combination said strips have their narrow edges exposed to said face, and in which said straps are secured adjacent the ends of said strips by means of a single fastening member passing through said strap and into the narrow edge of the said strip.

3. In a shipping crate, a framework for defining the faces of the crate, at least one of the faces being comprised of a plurality of oppositely disposed strips of material having their flat faces exposed to the face of the crate, and means for reenforcing the said face, said means comprising a plurality of metal straps disposed diagonally across the said face and having their ends secured to the said flat faces of the said strips adjacent the diagonally opposite corners thereof.

4. In a shipping crate, a framework defining the faces of the crate, sheathing for at least one of the faces of the crate, and means for reenforcing said face of the crate and said sheathing, said means comprising a plurality of metallic straps disposed diagonally to said face and secured adjacent the opposite corners thereof.

5. The combination according to claim 4, in which said sheathing is comprised of a plurality of strips of lumber and in which said straps are interlaced with said strips.

6. In a shipping crate, a frame defining the edges of one face of the crate, and a pair of lengths of metal strapping, the straps crossing one another and the ends of the

straps being fastened to diagonally opposite parts of the frame.

7. A shipping crate having a frame made out of a plurality of strips of lumber, two 5 opposite strips having faces in substantially the same plane, and metal straps crossing one another and fastened to diagonally opposite parts of said faces of said strips.

8. A shipping crate comprising frame 10 members, and having diagonally disposed metallic tension members secured to opposite members of the frame.

9. A shipping crate made up of a plurality of strips of lumber fastened together 15 to form a framework defining the edges of the crate, and diagonal braces in the form of crossed strips of metal strapping fastened to the framework to reinforce it.

10. In combination, a pair of spaced- 20 apart boards whose flat sides are nailed to the edges of a second pair of spaced-apart boards to form a frame, and diagonal strap iron braces for the frame, the ends of the braces being nailed to the boards of a pair.

11. In combination, means constituting a 25 face a shipping container, said means including material extending over an intermediate portion of said face, and a plurality of metal straps secured diagonally across said face of the container to reinforce the same against diagonal strains, said straps being passed under said material to reinforce the same against inwardly directed thrusts.

12. In combination, means constituting a 30 face of a shipping container, said means including material extending over an intermediate portion of said face, and a plurality of metal straps disposed diagonally across the said face of the container and secured thereto, said straps being sufficiently free to move with relation to each other at their point of intersection to permit of a slight resilient action of said face, and said straps being passed under said material to reinforce the same against inwardly directed thrusts.

13. In combination, means constituting a 35 face of a shipping container, said means comprising a plurality of strips of material united to each other to constitute the frame-work and sheathing of said face, and a plurality of metal straps, said straps being passed under certain of said strips to reinforce the same against inwardly directed thrusts and being secured diagonally across the framework to reinforce the same against diagonal strains and being sufficiently free at their point of intersection to permit of a slight yielding movement with 40 relation to each other.

14. In combination, means constituting a 45 face of a shipping container, said means comprising a plurality of pieces of material united to each other to constitute the

frame-work and sheathing of said face, and a plurality of metal straps disposed diagonally across said framework and secured thereto, said straps being constructed of thin yieldable material and being interlaced 70 with said pieces of material.

15. In combination, means constituting a 75 face of a shipping container, said means comprising a plurality of pieces of material united to each other to constitute the framework and sheathing of said face, and a plurality of metal straps disposed diagonally across said framework and sheathing, but secured thereto only adjacent the corners of the face and free to move slightly 80 with reference to each other at their point of intersection, said straps being passed under at least a portion of the sheathing material.

16. In a shipping crate, a framework defining the faces of the crate, sheathing for 85 at least one of the faces of the crate and means for reinforcing said crate against diagonal strains and said sheathing against inwardly directed thrusts, said means comprising a plurality of metallic straps passed under at least part of said sheathing and disposed diagonally to said face and secured 90 adjacent the opposite corners thereof.

17. A shipping crate comprising a frame 95 for a face of the crate, said frame being composed of a plurality of pairs of strips of lumber, said pairs being united at their ends, sheathing material secured to the frame to cover an intermediate portion thereof, 100 said sheathing material being placed intermediate one of the pairs of strips and secured to the other of the pairs of strips, and a plurality of metal straps secured diagonally across said face of the crate to reinforce the same against diagonal strains, said straps being passed under said sheathing material to reinforce said material against inwardly directed thrusts.

18. In combination, a plurality of pairs 110 of spaced-apart boards, the flat sides of the first of said pairs being secured to the edges of the second of said pairs to form a frame, a plurality of metal straps disposed diagonally to said frame to reinforce the same against diagonal strains, sheathing material for said frame, said material being placed intermediate said first pair of boards and secured to the edges of said second pair of boards, and said diagonal straps having 115 their ends secured to the flat faces of said first pair of boards and having intermediate portions running under said sheathing material.

19. In a shipping crate, a framework defining the faces of the crate, each face being comprised of a plurality of pairs of spaced-apart boards, the flat faces of one pair being secured to the edges of the second pair, the framework being so arranged 120

that each of said boards constitutes part of the framework of two adjacent faces of the crate, the flat face of each board being used for one face of the crate and the edge of 5 the board for the adjacent face thereof, sheathing for the faces of the crate, said sheathing comprising a plurality of slats se-

cured to the edges of said pairs of boards, and a plurality of metal straps disposed diagonally to said faces and interlaced with 10 the slats of the sheathing.

In testimony whereof I have affixed my signature to this specification.

ALBERT WEIGAND LUHRS.
